UNITED STATES PATENT OFFICE

GEORGE W. SMITH, OF LYNN, MASSACHUSETTS, ASSIGNOR OF ONE-HALF TO LEE ELLIS,
OF LYNN, MASSACHUSETTS

HINGED LAST

Application filed March 23, 1929. Serial No. 349,348.

This invention relates to hinged lasts and has for its object the provision of means for retaining in close contact at all times the adjacent curved surfaces on the two parts thereof and taking up the wear on these surfaces after the last has been in use for a considerable time.

This object is attained by the mechanism illustrated in the accompanying drawing.

10 For the purpose of illustrating the invention, one preferred form thereof is illustrated in the drawings, this form having been found to give satisfactory and reliable results, although it is to be understood that the 15 various instrumentalities of which the invention consists can be variously arranged and organized, and the invention is not limited to the precise arrangement and organization of these instrumentalities as herein 20 shown and described except as required by the scope of the appended claims.

Of the drawings:

Figure 1 represents an elevation of a last embodying the principles of the present invention.

Figure 2 represents a longitudinal section of a portion of same on line 2, 2, on Fig. 1.

Figure 3 represents a vertical section on line 3, 3, on Fig. 2 with the last lengthened.

30 Figure 4 represents a similar section with the last shortened, and

Figure 5 represents a similar section with the last partially shortened.

Similar characters indicate like parts 35 throughout the several figures of the drawing.

In the drawings, 10 is the fore part of a divided last having in its rear face a curved depression 11 extending transversely thereof.

40 Fitted to this depression 11 is a projection 12 formed upon the front face of the heel part 13.

The fore part 10 has a vertical slot 14 in its rear end and a similar slot 15 is formed in 45 the front end of the heel part 13, these slots 14, 15 being in alinement.

Disposed in these slots 14, 15 is a hinge element 16 consisting of a bar with holes 17 and 18 in the opposite ends thereof to receive dowels 19 and 20 positioned respectively

in the fore part 10 and heel part 13 and extend transversely thereof.

One of these holes, as for instance the hole 17, has a round dowel or pin 19 extending therethrough and about the axis of this pin or dowel the bar 16 is adapted to move in shortening or lengthening the last.

The hole 18 is preferably elongated as shown in the drawings.

The dowel 20 is of novel construction having a recess 21 in its periphery and extending lengthwise thereof with overhanging projections 22 at the opposite ends thereof.

Beneath the projections 22 are disposed the beveled ends of a spring 23 which is longer than the recess 21 causing the center of the spring to curve or bow outwardly when positioned on the dowel.

The center portion of the spring is always in contact with the outer wall of the hole 18 and tends to draw the adjacent surfaces of the projection 12 and depression 11 into firm contact at all times.

When after long use of the last these surfaces become worn the spring will take up the wear, thus prolonging the life of the last.

One end of the dowel 20 is preferably made square as indicated at 25 so that said dowel cannot turn about its axis when disposed in one of the parts of the last.

The bottom of the recess 21 is raised at the center as indicated at 26 in Fig. 2 to prevent the spring 23 becoming perfectly straight as it is desired to retain some curvature in the spring at all times.

When the last is lengthened the spring 23 will be considerably depressed and lock the two parts of the last together very rigidly so that it requires considerable effort to break the last.

The dowel 20 with its spring attachment is inexpensive to make and when installed in a last is most effective in operation.

It is believed that the operation and many advantages of the invention will be understood without further description.

Having thus described my invention, I claim—

1. A hinged last the two parts of which have abutting curved surfaces and alined ver-

tical slots in their adjacent faces; a hinge member in said slots provided with holes in the opposite ends thereof, one of said holes being elongated; and dowels positioned in said fore part and heel part and extending through said holes, the dowel extending through the elongated hole having a separate spring member extending lengthwise thereof adapted to contact with the outer end wall of said hole.

2. A hinged last the two parts of which have abutting curved surfaces and aligned vertical slots in their adjacent faces; a hinge member in said slots provided with holes in the opposite ends thereof, one of said holes being elongated; and dowels positioned in said fore part and heel part and extending through said holes, the dowel extending through the elongated hole having a spring extending lengthwise thereof adapted to contact with the outer end wall of said hole, the ends of said spring being bevelled and positioned in notches formed in said dowel.

3. A hinged last the two parts of which have abutting curved surfaces and aligned vertical slots in their adjacent faces; a hinge member in said slots provided with holes in the opposite ends thereof, one of said holes being elongated; dowels positioned in said fore part and heel part and extending through said holes, the dowel extending through the elongated hole having a recess in its periphery with overhanging projections at its opposite ends; and an outwardly curved spring positioned in said recess with its ends beneath said overhanging projections.

4. A hinged last the two parts of which have abutting curved surfaces and aligned vertical slots in their adjacent faces; a hinge member in said slots provided with holes in the opposite ends thereof, one of said holes being elongated; dowels positioned in said fore part and heel part and extending through said holes, the dowel extending through the elongated hole having a recess in its periphery with overhanging projections at its opposite ends; an outwardly curved spring positioned in said recess with its ends beneath said overhanging projections; and means on said dowel extending into said recess to prevent said spring from assuming a straight position.

Signed by me at 294 Washington St., Boston, Massachusetts, this 21st day of March, 1929.

GEORGE W. SMITH.
